UNITED STATES PATENT OFFICE

HENRY A. WISE WOOD, OF NEW YORK, N. Y., ASSIGNOR TO WOOD NEWSPAPER MANUFACTURING CORPORATION, OF NEW YORK, N. Y., A CORPORATION OF VIRGINIA

PRINTING COUPLE SUPPORTING MEANS

Application filed August 4, 1923, Serial No. 655,778. Renewed April 6, 1929.

This invention relates to the bearings of the printing couples of a printing press, and to the means for supporting the same and adjusting them.

5 The principal object of the invention is to provide a simple arrangement for supporting the impression and plate cylinders, and at the same time locating the impression cylinders in definite position and providing for 10 the adjustment of the plate cylinders toward and from them without necessitating precise positioning during manufacture or accurate machine work.

Reference is to be had to the accompanying drawings, in which

Fig. 1 is a side view of part of a printing press showing a preferred form of the invention and showing the shafts in section on a plane just outside the frame;

20 Fig. 2 is a plan; and

Figs. 3 and 4 are end views of the plate cylinder and impression cylinder bearings respectively.

I have shown the invention as applied to 25 a web perfecting press having two plate cylinders 10 and two impression cylinders 11.

For supporting these cylinders I have provided the frame with rough cast unfinished perforations in which are cast permanent

30 bushings 1500 of bearing metal having aligned bearing surfaces finished in the act of casting. They constitute means for carrying studs or shafts 151. On each of these shafts 151 are pivotally supported bearing plates

35 152. Each of these bearing plates carries an impression cylinder bearing preferably in the form of a lining 153, of soft metal cast in the bearing plate. These two bearings at opposite sides of the press carry one of the impression cylinders. It will be noted that they project 40 upwardly from the pivotal shaft 151 which supports them.

Beyond these are another similar set of 45 shafts or studs 154 carried in the frame and supporting a pair of bearing plates 155 projecting upwardly in the same way. These have plate cylinder bearings 156 of soft metal arranged in alignment.

On the frame there are two projections 157 50 which have rough cast unfinished perfora-

tions in alignment with each other and are provided with a bushing 158 of soft alloy cast therein with finished surfaces. Each bushing 158 is a complete cylinder with a flat flange at one end or both. Through these extends a screw rod 159 one being located on each side of the machine. Each screw rod passes through perforations 160 and 161 in the bearing plates 155 and 152 respectively, the former perforation being smooth and the latter screw-threaded.

By means of nuts 162 the impression cylinder bearings are forced up against the projections 157 which have the soft bushings 158 provided with flat flanges projecting 55 therefrom and held in fixed position. By means of adjusting collars 163 the position of each of the plate cylinders is adjusted along the rod 159 in a very convenient and simple way and to any degree of fineness. 60 This forms an inexpensive and simple method of mounting all the cylinders accurately and solidly locating the impression cylinders and regulating the pressure of each couple.

The shafts 151 and 154 are mounted in the 65 bushings or bearings 1500 which are formed of suitable metal and cast in finished position on the frame of the machine around master shafts or studs so as to line up the said bushings. Thus, the machining and finishing of 70 the frame for the purpose of supporting these shafts is entirely avoided. Also by mounting the cylinders not on these shafts 154 and 151, but on shafts pivotally supported thereon, the adjustment of the cylinders is provided 75 for without any finishing or machining. Of course the studs of the cylinders themselves are mounted in the bearing bushings 153 and 156 cast in the bearing plates 152 and 155 in a 80 finished condition so as just to fit the studs of 85 the cylinders. All finishing therefore is eliminated at this point. The additional adjusting rods 159 are also so mounted that there is no finishing of the machine frame in 90 order to mount them in position and adjust 95 the cylinders by their aid.

It will be obvious therefore that all of the cylinders of the two printing couples may be brought into correct operative relation by very simple adjustments. Yet this requires 100

no precise positioning of the parts during manufacture such as machining of the frame and fitting the parts. The frame is simply cast with holes or passages through which the 5 studs are to pass. These passages are simply cast in a rough state larger than they are to be made eventually. They need not be smooth or even accurately located with respect to each other. This constitutes a material economy 10 in the manufacture and setting up of the press besides securing a very accurate and conveniently operated adjustment for the plate cylinders.

Although I have illustrated and described 15 only one form of the invention and shown it as applied to only one form of press, I am aware of the fact that modifications can be made therein by any person skilled in the art without departing from the scope of the invention as expressed in the claims. Therefore I do not wish to be limited to all the details of construction herein shown and described, but

What I do claim is:—

25 1. In a printing press, the combination with a printing couple, of means for supporting both of the printing cylinders on axes below the centers of the cylinders, and means for positioning the said cylinders with relation to one another located above the level of the said supporting means.

30 2. In a printing press, the combination with the plate and impression cylinders, of pivotally mounted bearings for each of said cylinders, and a device for adjusting the bearings of both cylinders about their pivots toward or from each other.

35 3. In a printing press, the combination with the press frame having a projection provided with a passage therethrough, of a screw rod extending through and supported in said passage, a pair of parallel shafts on the frame, a bearing piece pivotally supported on each of said shafts and having a bearing for the 40 plate and impression cylinder shafts respectively, means on said screw rod for clamping the impression cylinder bearing piece against the projection in fixed position, and means on the screw rod for adjusting the plate cylinder bearing piece toward or from the impression cylinder and holding it.

45 4. In a printing press, the combination with the press frame provided with a passage, of a screw shaft extending through and supported in said passage, a shaft on the frame, a bearing piece pivotally supported on said rod and having a bearing for the plate cylinder shaft, and means on said screw rod for adjusting the plate cylinder bearing piece toward or from the impression cylinder, and holding it.

50 5. In a printing press, the combination with a press frame having a projection provided with a passage therethrough, of a screw rod extending through and supported in said

passage, a bearing piece pivotally supported on the frame and extending upwardly from its pivot, and having a bearing for the impression cylinder shaft, and means on said screw rod for clamping the impression cylinder bearing piece against the projection in fixed position.

55 6. In a printing press, the combination with the frame having a projection provided with a passage therethrough cast in rough form and unfinished inside, and bushing of relatively soft alloy cast in said passage and finished inside in the act of casting and having a flat flange on the end also finished flat in the act of casting, of a screw rod fitting in said finished inside surface of the bushing, a bearing piece pivoted on the frame and having a passage through which said screw rod passes, the end of which is adapted to rest and fit against said flange, and means for clamping the bearing piece up against the flange.

60 7. In a printing press, the combination with the frame having a passage therethrough cast in rough form and unfinished inside, of a bushing of relatively soft alloy cast in said passage and finished inside in the act of casting, a screw rod fitting in said finished inside surface of the bushing, a bearing piece pivoted on the frame and having a passage through which said screw rod passes, and means for clamping the bearing piece up against the end of the bushing.

65 8. The combination with a printing press frame, and a cylinder forming a member of a printing couple, said frame having rough cast unfinished openings therein located at a distance from the center of said cylinder, of bearings of soft alloy cast in said openings, with their surfaces finished in the act of casting, and means resting in said bearings for pivotally mounting said cylinder.

70 9. In a perfecting printing press, the combination with two printing couples, of means for supporting the cylinders of said couples on axes below the center of the cylinders, and means for positioning the said cylinders with relation to each other located above the level of the said supporting means.

75 10. In a printing press, the combination with a printing couple, of supporting means therefor consisting of two levers at each end of the said couple, each lever secured upon an independent fulcrum, with means for varying the distance between the cylinders of the said printing couple.

80 11. In a perfecting printing press, a pair of printing couples set upon substantially the same plane, levers resting upon fulcrums for supporting the printing cylinders, and interconnected means for securing them in their correct relative positions.

85 12. In a printing press, the combination with an impression and a plate cylinder, of

means for adjusting both cylinders toward each other thus maintaining the paper line at the same point after any adjustment.

13. In a perfecting printing press, the combination with two printing couples arranged substantially in alignment, of means for adjusting the two cylinders of each couple simultaneously into closer or more distant contact to change their pressure on the paper but not the position thereof.

In testimony whereof I have hereunto affixed my signature.

HENRY A. WISE WOOD.
